UNITED STATES PATENT OFFICE

EMIL BARTHES, OF SALINAS, CALIFORNIA

HEEL PROTECTOR

Application filed June 12, 1929. Serial No. 370,262.

My present invention relates to heel protectors for shoes and more particularly to a protector for the protection of the rear portion of ladies' shoes against damage, as when driving an automobile.

The object of my invention is to provide a new and novel form of protector which is an improvement upon the protector disclosed and claimed in my prior Patent Number 10 1,571,466, dated February 2, 1926.

It is well known that in driving automobiles, the heel and rear portions of the driver's shoes rest on the floor of the car and become marred, scratched and worn. This 15 situation is particularly objectionable to ladies, since their shoes, being of a finer texture, very quickly become soiled and worn from this cause.

In the accompanying drawing I have illustrated one specific embodiment of my invention, but it will be understood that the invention can be otherwise embodied and that the drawing is not to be construed as defining or limiting the scope of the invention, 25 the claims appended to this specification being relied upon for that purpose.

Referring to the figures of the drawing:

Fig. 1 illustrates the use of my invention.

Fig. 2 is a perspective view of my improved 30 heel protector.

Fig. 3 is a sectional view thereof.

In the preferred embodiment of my present heel protector, I propose to construct the heel protector of a moldable material and 35 preferably of a molded celluloid compound. However, I desire to have it understood that the nature of the material is immaterial so long as it possesses characteristics which will render it relatively stiff and at the same time 40 flexible so that, when it is fitted upon the shoe, it will grip the same and thereby retain itself in position independently of any additional securing means.

In the drawing, 10 designates the heel protector as a whole, wherein it is shown as shaped to conform to the rear portion of the shoe and having a heel portion 11 formed integrally with the sides and back. The casing is constructed, as stated above, of a relatively 50 stiff material and when the parts are

formed as illustrated with the sides curved inwardly at their upper portion, both with respect to a vertical plane and a horizontal plane lying at approximately the central part of the casing, there will be a corresponding 55 action by the sides against the rear portion of the shoe. The inside of the casing will preferably be lined with a soft material such as velvet or felt 12, but with respect to this lining I desire it understood that it may 60 be omitted where the material of which the protector is formed will not be injurious to the shoe.

When the heel protector is constructed as above outlined, it will be found that it can 65 be readily slipped upon the shoe in a convenient manner, where it will firmly retain itself against displacement.

The construction and use of my invention, it is believed, will be obvious from the 70 above description. When desiring to use the protector, the driver will merely snap the same over the heel portion of the shoe, as indicated in Fig. 1. In this action, it will be understood, the sides will yield outwardly 75 and because of their natural resilience engage the sides of the shoe so as to hold the protector firmly in place. When leaving the driver's seat, the protectors can be very conveniently removed without delay or effort 80 and, as a result, by the use of my invention, the driver's shoes will be protected against being soiled and worn as at present is so common.

Having thus described my invention, what 85 I claim and desire to secure by Letters Patent is—

1. A heel protector constructed of resilient material and comprising a casing having flexible side and rear portions formed in one 90 piece and adapted to snugly fit over and about the heel of the rear portion of a shoe, and a bottom portion adapted to fit over the bottom of the heel and hold the sides of the casing in spaced relation, the top and front 95 portion of the casing being open and circumscribed by the marginal portion of the protector at the top of the casing and at the front edge of the casing and heel portion thereof, whereby said bottom portion will re- 100

inforce and stiffen said side portions, the side portions at the top and front being extended forwardly beyond the front edge of the said bottom portion and converging to their front edges so as to clamp the protector in position on the shoe through the resiliency of the material.

2. A heel protector constructed of resilient material and comprising a casing having flexible side and rear portions formed in one piece and adapted to snugly fit over and about the heel of the rear portion of a shoe, the top and front portion of the casing being open and the side portions at the top and front being extended forwardly beyond the front edges of the bottom of the side portions and converging to their front edges so as to clamp the protector in position on the shoe through the resiliency of the material, and means connected with the side portions for normally holding the side portions in a pre-determined spaced relation.
